OP D 16,641

DESIGN.

—o—
A. PETZOLD.

RUG.

No 16,641.

Patented Apr. 20, 1886.

UNITED STATES PATENT OFFICE.

ADOLPH PETZOLD, OF PHILADELPHIA, PENNSYLVANIA, ASSIGNOR TO JOHN BROMLEY & SONS, OF SAME PLACE.

DESIGN FOR A RUG.

SPECIFICATION forming part of Design No. 16,641, dated April 20, 1886.

Application filed March 11, 1886. Serial No. 194,902. Term of patent 3½ years.

To all whom it may concern:

Be it known that I, ADOLPH PETZOLD, a citizen of the United States, and a resident of Philadelphia, Pennsylvania, have invented and produced a new and original Design for Rugs, of which the following is a specification, reference being had to the accompanying photographic illustration, to which reference is made.

- 10 In the illustration, A is a central figure or ground in the form of a sheet with torn or irregular side edges, which is covered with ornamental figures B, resembling daisies of various sizes, with scrolls C C and dots D D. 15 The space between the edges of this interfigure A and the edges of the rug is interspersed with bunches of flowers E E in the form of lilacs, and smaller sprays H H of the same, as well as small detached clusters I I. The upper and lower edges of the central figure, A, are bounded by straight borders K K, ornamented as shown. The larger bunches of flowers E E are located in the spaces between the irregular ends of the central figure, A, and the

sides or ends of the rug design. The long 25 edge of the rug is the top. The sides of the rug are formed by the narrow ends.

The essential features of my design are the central figure, A, with its upper and lower borders, consisting of straight edges and its 30 torn or irregular sides, its ground being ornamented with star or daisy shaped figures, and the end clusters or bunches of flowers resembling sprays of lilacs in form.

What I claim as new is--

35 A design for rugs, consisting of the central figure, A, with its upper and lower borders, consisting of straight edges with torn or irregular sides, its ground being ornamented with star or daisy shaped figures, and the end 40 clusters or bunches of flowers resembling sprays of lilacs in form, substantially as described and shown.

ADOLPH PETZOLD.
